Primary Examiner — Sharon S Oum(74) *Attorney, Agent, or Firm* — CANTOR COLBURN LLP(57) **CLAIM**

The ornamental design for an axial flow fan, as shown and described.

DESCRIPTION

FIG. 1 is a perspective view of an axial flow fan, showing my new design;

FIG. 2 is a front view thereof;

FIG. 3 is back view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view thereof 1 taken along line 8-8 of FIG. 2.

The broken lines illustrate portions of the axial flow fan and form no part of the claimed design.
